COMBINATIONAL CODE ENTRY CONTROLLING MEANS FOR ACCUMULATORS

Horace S. Beattie, Poughkeepsie, N. Y., assignor to International Business Machines Corporation, New York, N. Y., a corporation of New York

Application December 9, 1944, Serial No. 567,435

10 Claims. (Cl. 235—61.6)

1

This invention relates to record controlled accounting machines and more particularly to improvements in the digit entering mechanisms for accumulators.

The present improvement was devised primarily to provide a practical form of entering mechanism for an accumulator operable according to the decimal notation system under control of a card perforated according to an arbitrary code which is selected to fit in the scheme of operation.

The prior art is replete with various forms of entering mechanisms for accumulators operable according to the decimal notation system in which the control element therefor, such as a card, keys, etc., is indexed in the same system. The indexing of the card in the same system, best exemplified as the Hollerith card, presents many advantages with corresponding disadvantages; namely, in the area occupied by the perforations providing the index point positions for the denominational columns. Cards perforated according to a combinational hole system surmount this objection but result in the disadvantage of requirements for code translators, converters, and the like to effect accumulator operation according to the selected notation system.

It is, therefore, the main object of the present invention to provide an entering means under control of coded designations which is simple in construction and embodiment, practical in construction and operation and which possesses many features which render coded designations useful and practical for operation of card controlled accounting machines.

Another object of the invention is the provision of an entry mechanism operable during varying periods of digit entering operations which provides for the selective entry of digits in an accumulator, which digits entered alone or in predetermined combinations effect entries according to the desired notation system.

A still further object of the invention is to select such digit entries under control of card perforations arranged according to an arbitrary code and which are assigned digital values according to an established system.

In carrying out the fundamental and basic features of the invention, the digits of the system which are selected are arbitrary but must conform to the requirement that the digits alone or in combinations will effect all of the digit entries required in the notation system. In the decimal system there are many such combinations of digits, such as 1, 2, 2, 4; 1, 1, 2, 5; 1, 2, 55

2

4, 6 and 2, 1, 3, 4 herein employed for the purpose of illustration. Proper selection of digits reduces the number of perforations located in a card column, thus requiring less than nine perforations which have been previously used in the Hollerith type of card to express the digits 1-9, inclusive in the decimal system. Accordingly, the proper selection of the assigned values to the perforations used, singly or in combination, reduces the card area perforated to express and represent numbers. With this understanding, it is obvious that the perforations do not represent digits by virtue of their differential locations as in the Hollerith type of card, but by the arbitrary values of the digits assigned to them, and function therefore by proper correlation with the entering mechanism to selectively determine the appropriate entries in the accumulator.

A still further object of the invention is to correlate the entering mechanism with the analyzing mechanism in such manner that the card, perforated to represent the assigned values, can be analyzed while in motion. By feeding the card past a single analyzing means the latter can be rendered effective in succession to determine the particular digit entries to be made in the entering cycle.

The accumulator preferably employed in connection with the present invention is of a type well known in the art wherein the initiation of a digit entering operation is effected by transmission of a start impulse to a start or advance electromagnet which couples the accumulator element to a driving shaft and wherein the entry

operation for the accumulator element may be terminated by transmitting an impulse to a stop electromagnet which has the designated function. Accordingly, in the adoption of this form of accumulator with the present invention the digit entry is initiated and terminated in operation by impulses transmitted to the respective start and stop magnets. For additive operations the start magnet receives impulses under control of the card perforation analyzing means at predetermined times in the entering cycle of operation.

The impulse transmitting means associated with the stop magnet is effective after transmission of each start impulse to transmit an impulse to the stop magnet to terminate the digit entering operation, if it was initiated. By suitably spacing the timing of successive start and stop impulses, digit entering periods of various durations are provided which effect the entry of the desired digit in the accumulator element. The analyzing means is effective at the

time a perforation is analyzed to transmit an impulse to the start magnet. Hence, this novel correlation between the analyzing mechanism and the start magnet and the cyclically operable impulse transmitting means and the stop magnet enables the initiation of digit entering periods of durations to cause the entry of digits in the accumulator equivalent to the assigned digital values of the perforations. The above construction carries out the objects of the invention in a manner which is distinguished by its simplicity and effectiveness in operation.

A still further object of the invention is to enable the entering mechanism to operate in a subtractive manner to enter the nines complements of each digit in the accumulator when subtracting operations are to be selectively effected. By appropriate selection, all derived from a supplemental cyclically operable impulse transmitting means rendered effective when subtraction is to be performed, impulses are transmitted to the start magnet at the beginning of a subtracting entering cycle. The analyzing means is correlated with the stop magnets when subtraction is to be performed so that such impulses terminate subtracting operations when nines complements of the digits represented in a denominational column are entered in the accumulator. The provision of this subtraction scheme augments the usefulness of the additive entering arrangement without detracting from the feature of simplicity in construction and effectiveness in operation.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a diagram of the electrical wiring connections.

Fig. 2 is a timing diagram.

Fig. 3 shows part of a record perforated according to the arbitrary code to represent the digits 1-9 and 0, as well as X to represent a negative amount to be subtracted.

Fig. 4 is a view in side elevation of an assembled accumulator unit of a construction shown in detail in Patent No. 2,328,653.

The present improved system for effecting item entries is applicable to record controlled machines having cards perforated according to a combinational hole system.

It has been shown as a matter of illustration as applied to a machine of the type in which multiple index point positions are perforated in the card columns and in which the cards are adapted to be analyzed while in motion. The particular type of machine does not enter into the present invention, as any other type of machine in which holes are analyzed would serve for the purpose of explanation and embodiment equally as well. Reference may be had to the patent to A. W. Mills, No. 2,079,418, and particularly to Patent No. 2,161,589, E. J. Rabenda, for a machine of the type to which the present invention is particularly adaptable.

Referring now to the wiring diagram (Fig. 1), the machine is provided with a card feed clutch magnet 10, shown in the upper part of Fig. 1, which when energized, will cause the feeding of record cards in a record controlled machine in the usual manner from the supply magazine so that they will move past the upper brushes UB

and, exactly one machine cycle later, pass the lower brushes LB. The machine is driven by a motor M which is placed in continuous operation by closing the power supply switch S. Depression of the start key to close contacts 11 will complete a circuit from one side of line 12, through start key contacts 11, card feed clutch magnet 10, relay contacts M1a, stop key contacts 13 to line 14. In parallel with clutch magnet 10 is a relay R5 which is energized concurrently therewith to close its contacts R5a.

As the cards subsequently pass the lower brushes LB, the usual card lever contacts LCL close to complete an obvious circuit through the lower card lever relay LCLM which will close its contacts LCLMa, providing the holding circuit for the LCLM relay extending from line 12 to relay LCLM, contacts LCLMa, cam contacts CF7 to line 14.

It may be pointed out at this time that in the circuit diagram there are shown various cam controlled contacts. Those designated with the prefix CF are in operation when the card feeding mechanism functions; those prefixed CR are constantly in operation.

Relay magnet LCLM closes its contacts LCLMb to provide a holding circuit for the card feed clutch magnet 10 which is traceable from line 12, contacts LCLMb, R5a, magnet 10, contacts M1a, stop key contacts 13 to line 14.

Machines of the type to which the present improvements are preferably applied have also incorporated therewith a group control mechanism which enables the successive feeding of cards containing the same classification or group control designation without interruption. Upon a change in group classification the group control mechanism will function to energize the M1 relay, thereby opening its M1a contacts to permit interruption of the card feed clutch magnet circuit when cam contacts CF12, which normally short-circuit contacts M1a, open at a predetermined point in the cycle of operations. The group control mechanism may consist of any suitable embodiment and could, for example, consist of the specific arrangement shown in the patent to E. J. Rabenda, No. 2,161,589, granted June 6, 1939.

The present invention is capable of effecting entries additively as well as subtractively and the machine is conditioned for a subtracting operation whenever the upper brushes UB sense a special control designation at the X index point position.

Card lever relay contact UCLMa are controlled by a relay magnet UCLM connected through CF9 to a so-called card lever brush 15 which traverses the edge of the cards. When the brush 15 is not insulated from the contact roller by the presence of a card thereat, a circuit is completed from line 12, contacts CR1, CF11, relay contacts UCLMa, UB contact roller, brush 15, contacts CF9, relay UCLM to line 14. Relay UCLM closes its contacts UCLMb to establish a holding circuit through contacts CF2. Thus, as long as cards continue to feed, relay UCLM is not energized and its contacts UCLMa subsequently remain closed.

At this time it will be understood that when a perforation is at the X index point position of a card and is analyzed by the upper brush UB in the respective column, a circuit is closed from line 12, through cam contacts CR1, contacts CF11, relay contacts UCLMa, UB common contact roller, perforation at the X index point posi-

tion, upper brush UB to a plug socket 26. As will be later described, a plug connection is made from such plug socket to transmit the impulse to a subtracting control relay R9.

As is well known in the type of machine now being described, entry operations are effected under control of perforations when the card is sensed by the LB brushes. The entry circuit in part is traceable from line 14, lower card lever contacts LCLM_c, cam contacts CF2, LB common contact roller, through the perforation in the card to a plug socket 18. The remainder of the entry circuit will be subsequently described and at this point it is explained that it is customary to effect plug connections 19 from such plug sockets to plug sockets 20 of the particular orders of the accumulator in which the entries are to be effected.

The entry of digits 2, 1 and 4 is directly initiated when holes at such digit positions are analyzed by the LB analyzing brushes. As shown in Fig. 3, to represent these digits a single hole is located in a column at a corresponding code position.

The impulses for initiating the operation of the accumulator elements, transmitted as the particular card holes 2, 1, 4 are analyzed, is directed from plug connections 19 to plug sockets 20 and thence serially through the following relay contacts, all of which are at normal at the time the impulses are directed. For the units order the circuit extends from the units order plug socket 20, thence through relay contacts R6U, TSBU, RS2U, R7U, RS1U, to the advance magnet AM of the units order, thence by a wire 25 to the line 12. Thus, referring to the timing diagram of Fig. 2 the advance magnet AM is energized at differential times, dependent upon the particular card hole analyzed and accordingly the accumulator element is initiated into operation at differential times. The accumulator element rotates until a following impulse is directed to the stop magnet SM under control of cam operated contacts by a circuit now to be described.

For a digit entry of 2 the accumulator element is retained clutched until said element is rotated to the extent of two clutch teeth. The digit entry of 1 is initiated at a later time when the 1 hole is analyzed so that the accumulator element will be clutched to the extent of only one clutch tooth before it is declutched. For the entry of 4, the accumulator element is clutched at the time that the 4 hole is analyzed and will remain clutched until the element is rotated to the extent of four clutch teeth.

The impulses which are directed to the stop magnet SM to terminate additive digit entering operations are directed by the cam contacts CR3, the circuit extending from the line 14 through cam contacts CR3, thence through the R8 relay contacts which are transferred just prior to the time that the CR3 contacts transmit an impulse, thence through the stop magnet SM of the related order, wire 25, to the line 12. The R8, U, T and H relay contacts for the three denominational orders shown herein are transferred upon the energization of the R8 relay which is energized at times under control of the CF10 contacts. The circuit for repeatedly energizing the R8 relay extends from the line 14, through CF10 contacts, R8 relay, to line 12.

Referring to the timing diagram, it will be observed that the CR3 contacts close at three different times during the operating cycle but

shortly prior to each closing of the CR3 contacts the CF10 contacts are closed, insuring that the R8 relay contacts have been transferred prior to the initiation of the accumulator operation terminating impulse directed by the CR3 contacts.

It is desirable to energize the stop magnet SM prior to the time that the accumulator element has rotated the full extent of a tooth, giving sufficient time for the train of parts leading from the SM magnet to the accumulator declutching mechanism to operate to declutch the accumulator element after the rotation of a full tooth has been secured. This is the reason for transmission of the CR3 impulses at the particular times shown. It is also pointed out that CF10 contacts are closed before and also after the closing of the CR3 contacts to insure that the time for the energization of the stop magnet SM is fully utilized.

For the entry of the digit 2 or 1, the accumulator element is rotated to the extent of two teeth or one tooth, respectively, dependent upon the hole analyzed and after such extent of rotation the first closure of cam contacts CR3 energizes the stop magnet SM to terminate the 2 or 1 digit entry. The second impulse directed by the CR3 contacts is timed so as to declutch the accumulator element after a rotation to the extent of four clutch teeth to terminate a 4 digit entry.

As designated in Fig. 1 and hereinbefore stated, it is preferred to utilize the type of accumulator unit fully shown and described in the Patent No. 2,328,653, issued to C. D. Lake, et al., granted

September 7, 1943.

The construction and operation of this unit is fully shown and described in this patent and therefore only a brief reference is necessary herein. In Fig. 4 some of the major elements of the units are shown identified by the same reference numerals as in the patent.

The pivoted armature 45 is between the cores of the advance magnet AM and the stop magnet SM and said armature had a connection to a clutch lever 21. In the declutching position of the clutch lever 21, shown in Fig. 4, the armature 45 is biased against the core of the SM magnet. Whenever the AM magnet is energized, the armature 45 will take an alternative position, rocking the clutch lever 21 to a clutching position. The clutch lever 21 is held in either clutching or declutching position by a latch 35.

A feature of the accumulating unit is that the armature 45 will remain biased by latch 35 against the energized AM or SM magnet that last attracted it.

Clutch lever 21 is shown in declutching position and when moved to an unclutching position it releases a disk 20 for counterclockwise movement, and a spring 31 is now effective to rock a clutch pawl 30 into engagement with a ratchet wheel 16. The latter is fixed to a constantly rotating gear 17 and therefore the ratchet wheel 16 constantly rotates. As a result of this clutching operation an accumulator element 24, shown in Fig. 1, is initiated in rotation. The termination of the rotation of the accumulator element is effected as a result of the energization of the SM or stop magnet. This will attract the armature 45, rocking the clutch lever 21 to declutching position.

For reasons that will be clearer later on it is preferable not to initiate the 3 digit entry when the hole having the assigned digital value 3 is analyzed but to store up the digit representation

in a relay for each order which initiates the 3 entry at a later time in the operating cycle.

Prior to the time the 3 digit representing hole is analyzed, cam contacts CR2 close and by an obvious circuit R6 relay is energized to transfer its R8, U, T, H contacts. Then when the 3 hole is analyzed a circuit will be closed which, for the units order, extends from the related plug socket 20, through the R6U relay contacts now transferred, to the pickup winding of a related storage relay R8, to line 12. The pickup winding of each energized relay closes the respective stick relay contacts R3A and the stick circuit for each relay extends back through CR5 cam contacts to line 14.

Shortly before CR4 cam contacts close at about 191°, cam contacts CF13 close and by an obvious circuit energizes the TSB relay to transfer the TSB, U, T, H relay contacts. While such relay contacts are closed and also the R3B relay contacts in the order in which a 3 digit entry is to be effected, an impulse is transmitted at about 191° by a circuit from line 14, through CR4 cam contacts, R3B relay contacts of the order in which a storage relay was energized, thence through the related TSB relay contacts now transferred, serially through the following relay contents now at normal RS2, R7, RS1 to the advance magnet AM to line 12. This will initiate the accumulator operation for the entry of the 3 digit and the accumulator wheel will rotate to the extent of three clutch teeth.

The third impulse directed by the CF10 contacts will energize the R3 relay and the latter will transfer its contacts in each denominational order. Thereafter, the third impulse directed by the CR3 cam contacts will be transmitted through the transferred relay contacts of the R8 relay to the stop magnet SM of each denominational order. When initiation of the accumulator element is effected in any order for the digit 3, energization of the SM magnet at this time will terminate such 3 digit entry. The impulses transmitted by CR3 to the stop magnet SM of other orders will be ineffective because each armature 45 is against the core of the SM magnet.

The preceding description has described the operation of the machine for the entry of the basic digits 1, 2, 3 and 4. From the code shown in Fig. 3 it is evident that the remaining digits 5-9, inclusive, are entered by a combination of the basic digit entries. For example, entry of the digit 5 is effected by combination of the digit entry 1 and 4. The digit entry of 6 is obviously effected by the successive entry of the digit 2 and the digit 4, etc.

It is thought unnecessary to give further description of the manner of operation of the machine for entry of combination of digits, since this is carried on precisely in the same manner and by the same circuits previously described in detail for the basic digits. However, it should be observed that for entry of the digits 7, 8 and 9 the digits 3 and 4 are separately entered. Since these 3 and 4 entries cannot occur concurrently because a 4 digit entry would overlap a 3 digit entry, it is desirable to store up one of these digit representations to control a successive entry. Herein, the digit 3 is stored up, as previously explained.

It is desirable that zeros be represented by holes at the 0 index point position in columns at the left of the significant digit of the highest denominational orders. It is further common

practice to punch zeros at the left of such significant digit to show that all card columns of a card field have been punched. To prevent impulses from being directed to the advance magnet AM when such holes are analyzed, it is explained that the cam operating the CF2 contacts does not have a high cam portion to close such contacts when the 0 holes are analyzed. This omission is evident from the timing diagram (Fig. 2). Hence, no impulses will be transmitted to the AM magnet when 0 representing holes are analyzed in any card column.

Subtraction

15 The machine also includes an arrangement whereby specially characterized records will effect subtraction of the amounts represented by the perforations. A hole at the X index point position of the card shown in Fig. 3 conditions the

20 machine to enter an amount negatively.

The plug socket 26 associated with the brush which analyzes the X designation is plug connected to plug socket 40, wired to the R9 relay. When the X hole is analyzed by a UB brush a 25 circuit is closed from line 12, through CR1 contacts closed at the time the X hole is analyzed, through CF11 cam contacts also closed at this time, thence through UCLMa relay contacts now closed, UB analyzing brush, plug socket 26, plug 30 connection to plug socket 40, pickup winding of the R9 relay to line 14. R9 relay closes its stick contacts R9A and a stick circuit for R9 relay extends back to line 12, through R9A relay contacts and stick cam contacts CF5. The latter 35 holds the R9 relay energized for the remainder of the cycle and for a short period at the beginning of the succeeding entry cycle.

R9 relay closes its relay contacts R9B and with the latter closed at the time CF6 cam contacts 40 close at the beginning of the next entry cycle a circuit is closed from the line 14, relay contacts R9B, cam contacts CF6, pickup winding of the RS relay to line 12. The pickup winding closes stick contacts RSA and a stick circuit for the holding winding extends from the line 12, CF14 cam contacts, stick relay contacts RSA, holding winding of the RS relay, RS1 and RS2 relays to the line 14. The RS1 and RS2 relays now transfer their respective U, T and H contacts.

50 The transfer of the RS1 relay contacts coordinates the CF4 cam contacts with the advance magnets AM of all denominational orders so that at predetermined times impulses directed by the CF4 cam contacts will energize the advance magnet AM of each order to tend to initiate digit entries 2, 4 and 3 in succession. The circuit for effecting this is from line 14, CF4 cam contacts, shifted RS1 relay contacts, the associated AM magnet to line 12.

55 As previously described, the CF10 cam contacts effect the energization of the R8 relay to enable the latter to close its contacts prior to the transmission of each impulse by the CR3 cam contacts. Such cam contacts are utilized in subtraction to transmit an impulse to the stop magnet SM of each denominational order to thereby terminate the 2, 4 and 3 digit entries. The circuit for effecting this is from the line 14, CR3 cam contacts, R8 relay contacts now transferred, the associated SM magnet to line 12.

60 The effect of such circuits is to provide the capability of normally entering in each denominational order the digit entries 2, 3 and 4 automatically in succession. The summation of such digit entries will enter a 9 in each denomina-

tional order that the corresponding card column is imperforate or represents 0, which does not control the entry of a digit. The presence of a hole in a card column will, in accordance with the digit represented thereby, cancel or nullify the corresponding digit entry in a manner now to be described.

The principle of operation may be expressed by the following table:

Digit Expressed in Card Column	Normal Successive Entries	Holes at	Nines Complement Entry
1	2, 4, 3	1	1, 4, 3=8
2	2, 4, 3	2	4, 3=7
3	2, 4, 3	3	2, 4=6
4	2, 4, 3	4	2, 3=5
5	2, 4, 3	1, 4	1, 3=4
6	2, 4, 3	2, 4	3
7	2, 4, 3	3, 4	2
8	2, 4, 3	1, 3, 4	1
9	2, 4, 3	2, 3, 4	0
0	2, 4, 3	0	2, 4, 3=9

For the entry of the complement of certain digits expressed in the card columns, such as digits 1 and 8, the normal 2 entry does not occur because the presence of a hole at the 1 position terminates the accumulator operation after a 1 entry. In this operation the CF4 cam contacts transmit an impulse to the advance magnet AM to initiate a 2 entry. Armature 45 will now be attracted by the core of the AM magnet. At the time the 1 hole is analyzed the impulse from the analyzing circuit extends from the plug socket 20 through R6 relay contacts now normal, thence through the TSB relay contacts now normal, thence through the transferred RS2 relay contacts, thence through the R8 relay contacts now normal, to the stop magnet SM to line 12. Energization of the stop magnet SM will attract the armature 45 to declutch the accumulator element. Thus, whenever a 1 is to be entered in a complement digit entry the normal 2 entry is shortened to result in the 1 digit entry.

For other complement digit entries, such as the entry of the nines complement of the digits 4, 5, 6, 7, 8, and 9, the normal 4 digit entry is cancelled or nullified. As previously stated, cam contacts CF4 transmit an impulse to the AM magnets of all denominational orders to normally effect the 4 digit entry in these orders. The 4 digit representing card hole nullifies this because concurrently with this impulse transmission to the AM magnet, an impulse is directed from the plug socket 20, through R6 relay contacts now normal, TSB contacts now normal, RS2 contacts now transferred, R8 relay contacts now normal to the stop magnet SM. Since, at this time, the armature 45 is already against the core of the SM magnet, concurrent impulses to the AM and SM magnets will not result in the clutching of the accumulator element. The reason for this is that the force of attraction exerted by the SM magnet on armature 45 will be greater than that exercised by the AM magnet because of the airgap between the armature 45 and the core of the AM magnet. Thus, for certain digits the normal 4 digit entry will be cancelled or nullified.

For the nines complement of the entry of the digits 2, 6 and 9 the normal 2 digit entry is cancelled or nullified in the same manner. Cam contacts CF4 transmit an impulse to the AM magnets of all denominational orders to normally effect the 2 digit entry. The 2 card hole nullifies this because concurrently with this

impulse an impulse is directed from the plug socket 20, through R6 relay contacts now normal, TSB contacts now normal, RS2 contacts now transferred, R8 relay contacts now normal, to the stop magnet SM.

For the nines complement entry of digits 3, 7, 8 and 9 the normal 3 digit entry is cancelled or nullified in the same manner. For the nines complement entry of digit 3 the cancellation impulse derived upon the analysis of the 3 card hole is stored up in a related R3 relay and the stored up reading is subsequently read out at the same time that the normal 3 digit entry is initiated. Upon the analysis of the 3 card hole an impulse is directed from the plug socket 20, thence through R6 relay contacts now transferred to the associated R3 relay magnet which is energized and held energized under control of the stick cam contacts CR5 in the manner previously described. Just prior to the time that the CF4 cam contacts close to initiate the 3 digit entry, CF13 cam contacts close to energize the TSB relay. Concurrent with the closing of the CF4 cam contacts to initiate the 3 digit entry, CR4 cam contacts close to transmit an impulse from the line 14 through the CR4 cam contacts, R3B relay contacts of the order in which the normal 3 digit entry is to be cancelled, thence through the TSB contacts now transferred, thence through the RS2 contacts now transferred, thence through the R8 relay contacts now normal, to the stop magnet SM. Hence, concurrent impulses to the AM and SM magnets will not result in the clutching of the accumulator element, and the 3 digit entry will be cancelled.

Whenever 9 is expressed in a card column the normal digit entries 2, 4 and 3 are all cancelled and there will be no operation of the accumulator element.

The above describes the cancellation by the card holes of certain digit entries. Where there is no cancellation of an entry due to the absence of a hole having that digit value the normal entry is effected. For example, in entering the nines complement of 5 the normal "2" entry is shortened to a 1 entry due to the presence of a 1 hole in the code arrangement. The 4 hole cancels the normal 4 entry. The normal 3 entry is effected because of the absence of a 3 hole. Thus, two successive entries 1, 3 effect a combined 4 digit entry which is the nines complement of 5. In the same manner other successive digit entries are effected where they are combined to effect a nines complement entry.

Units carry circuit

The accumulator of the type shown herein is also provided with a units carry control mechanism associated with a units carry circuit herein which is of the conventional arrangement. For this reason, such circuit will be described generally.

Considering now the units order accumulator wheel, when the latter passes from 9 to 0 the carry contact blade 42 (see Fig. 4) will be shifted and latched to engage the "10" carry contact 44. Shortly after 270° of the machine cycle, cam contacts CF1 close to energize the R1 relay, which latter transfers its U, T and H contacts. Thereafter, cam contacts CF3 close, closing the circuit from the line 14 through cam contacts CF3, through the aforementioned "10" units carry contact 44 and contact blade 42 of

the units order, thence through the R7T contacts now transferred, thence through the RS1T contact now in normal position, to the AM magnet of the tens order, causing the clutching of the accumulator element to effect a units carry to the tens order. 5

As fully shown in the patent to C. D. Lake et al., No. 2,328,653, a knockoff pin designated 53 in this patent serves at the end of a cyclical carry period to cause the accumulator wheel to be arrested after a carry entry. Of course, the knockoff pin 52 of the patented machine will not be used because herein the accumulator element is declutched at different times and by a different control means. 10

The so-called "nines" preparatory carry circuit is also provided in the type of accumulating unit shown herein and considering now the tens order, if the related accumulator wheel is standing at 9 as shown in Fig. 4, the "9" units carry control contact 43 will be engaged by the related contact blade 42 and the units carry impulse will be extended from the "10" units carry contact 44 and blade 42 of the units order, thence through the "9" units carry control contact 43 of the tens order, related contact blade 42, thence through the R7H contacts now transferred, the RS1H contacts now in normal position, to the AM magnet of the hundreds order. In the customary manner, this will effect a units carry to the hundreds order. 15 20 30

Entry of fugitive unit

Since subtraction is effected herein by the complemental process by the entry of the nines complement of the amount to be subtracted, it is customary to convert this amount to the tens complement by the entry of the fugitive unit. The carry mechanism of a selected order is employed as the instrumentality to effect this unit entry. 35

Referring to Fig. 1, a plug connection 46 is made between the units order and the highest denominational control order herein shown by way of example as the hundreds of thousands denominational order. Whenever the accumulator element of such order goes from 9 to 0, contact blade 42 will make contact with the contact point 44 and the unit carry impulse will be directed through such contact point 44 and contact blade 42, plug connection 46, thence through the R7U contacts now transferred, RS1U contacts now at normal, to the AM magnet of the units order. This will effect a units carry to the units order, converting the nines complement entry to the tens complement entry. 40 45

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims. 50

What is claimed is:

1. In a machine controlled by a card having holes arranged at index point positions according to a 4-hole code, representing digit entries 1, 2, and two other digit entries, which entries singly or in combination represent all digits 1-9 of the decimal system, means for sensing said index point positions to ascertain the presence of digit representing holes, an accumulator unit of the 75

type wherein the digit entry in an accumulator element is initiated by an impulse transmitted to a start magnet, and is terminated by an impulse transmitted to a stop magnet, cyclically operable impulse transmitting means for transmitting successive impulses to said stop magnet timed to occur at three different times, one to terminate either the 2 or 1 digit entry whenever the entry has been previously initiated by the sensing of the corresponding 2 or 1 hole, and the remaining two impulses to terminate the two other digit entries, and means under control of said sensing means to transmit an impulse to said start magnet to initiate a digit entry corresponding to the digit representing hole sensed. 15

2. In a machine controlled by a card having holes arranged at index point positions according to a 4-hole code, representing digit entries 1, 2 and two other digit entries A and B, which entries singly or in combination represent all digits 1-9 of the decimal system, means for sensing said index point positions to ascertain the presence of digit representing holes, an accumulator unit of the type wherein the digit entry in an accumulator element is initiated by an impulse transmitted to a start magnet, and is terminated by an impulse transmitted to a stop magnet, cyclically operable impulse transmitting means for transmitting successive impulses to said stop magnet timed to occur at different times to terminate each digit entry whenever the entry has been previously initiated by the sensing of a hole corresponding to such digit entry, other cyclically operable impulse transmitting means to transmit successive impulses, means under control of said sensing means to transmit impulses derived from said last named impulse transmitting means to said start magnet to initiate a digit entry whenever a hole 2, 1 or a hole representing the B digit entry is sensed, storage relay means, means under control of said sensing means for energizing said storage relay when a 3 hole representing the A digit entry is sensed during another digit entry if it occurs, and supplemental impulse transmitting means timed to transmit an impulse under control of said energized storage relay means after all previous digit entries have been effected to said start magnet to initiate the A digit entry. 35 40 45

3. In a machine controlled by a card having holes arranged at index point positions according to a 4-hole code, representing digit entries 1, 2, and two other digit entries A and B, which entries singly or in combination represent all digits 1-9 of the decimal notation system, means for sensing said index point positions to ascertain the presence of digit representing holes, an accumulator unit of the type wherein the digit entry in an accumulator is initiated by an impulse transmitted to a start magnet, and is terminated by an impulse transmitted to a stop magnet, cyclically operable transmitting means for transmitting successive impulses to said stop magnet, timed to occur at three different times, one to terminate either the 2 or 1 digit entry whenever the entry has been previously initiated by the sensing of the 2 or 1 hole and the remaining two impulses to terminate the A and B digit entries, other cyclically operable impulse transmitting means to transmit successive impulses under control of said sensing means to said start magnet to initiate a digit entry whenever a hole 2, 1, or B-digit representing hole is sensed, storage relay means, means under control of said sensing means for energizing said storage relay when an A-digit represent- 55 60 65 70 75

ing hole is sensed during another digit entry if it occurs, and supplemental impulse transmitting means timed to transmit an impulse under control of said energized storage relay means after all previous digit entries have been effected, to said start magnet to initiate the A digit entry.

4. In a machine controlled by a card having card holes arranged at index point positions according to a 4-hole code, representing digit entries 1, 2, and two other digit entries A and B, which entries singly or in combination represent all digits 1-9 of the decimal system, means for sensing said index point positions to ascertain the presence of digit representing holes, an accumulator unit of the type wherein the digit entry is initiated by an impulse to a start magnet, is terminated by an impulse to a stop magnet, and wherein an impulse to the start magnet concurrently with an impulse to the stop magnet is ineffective to initiate a digit entry, cyclically operable impulse transmitting means to transmit timed impulses to start magnet to initiate the digit entries 1, 2, and the two other entries A and B, other cyclically operable impulse transmitting means to transmit impulses to the stop magnet which are spaced from the first named impulses to terminate digit entries 2, and the two other digit entries A and B, and means controlled by said sensing means upon sensing holes representing the digit 2, and the two other digit entries A and B for transmitting impulses to said stop magnet concurrently with the transmission of an impulse to said start magnet by the first named impulse transmitting means to thereby render the start magnet ineffective to initiate a digit entry corresponding to the digit representing hole sensed; and upon sensing the 1 digit representing hole to transmit an impulse to said stop magnet which is spaced with respect to the impulse transmitted to the start magnet to initiate a 2 digit entry to terminate the digit entry operation when a 1 digit entry has been effected.

5. In a machine controlled by a card having holes arranged at index point positions according to a 4-hole code, representing digit entries 1, 2, and two other entries A and B, which entries singly or in combination represent all digits 1-9 of the decimal notation system, means for sensing said index point positions to ascertain the presence of digit representing holes, an accumulator element, means for initiating the operation of said accumulator element for a digit entry, means for terminating the operation of said accumulator element after a digit entry, cyclically operable means for causing said initiating means to be operative at different times to initiate digit entries 2, and the two entries A and B in said accumulator, other cyclically operable means for causing said terminating means to be operative at other different times to terminate digit entries 2, and the two entries A and B in said accumulator, and means controlled by said sensing means upon sensing perforations representing the digit representing holes 2, and the two entries A and B to cause the operation of said terminating means concurrently with the operation of said initiating means effected by the first named cyclically operable means to prevent the digit entry 2, and the two entries A and B corresponding to the digit value of the hole sensed, and upon sensing the 1 digit representing hole after initiation of the 2 digit entry to cause the operation of the terminating means for terminating the operation of the accumulator element when a 1 digit entry has been effected.

6. In a record controlled subtracting machine controlled by record cards wherein holes at a plurality of index point positions represent different digits, which holes singly or in combination represent all the digits of a notation system, means for sensing said index point positions to ascertain the presence of digit representing holes, an accumulator of the type wherein a digit entry is initiated by energizing a start magnet, is terminated by energizing a stop magnet, and the concurrent energization of the start and stop magnets prevents the initiation of a digit entry, means for transmitting impulses to said start magnet concurrent with the sensing of each of said index point positions to initiate digit entries in said accumulator corresponding to those represented by the index points, further means to transmit impulses to said stop magnet to terminate each of said digit entries, and means under control of said sensing means for transmitting upon sensing each digit representing hole an impulse to said stop magnet concurrent with the impulse transmitted by said first named impulse transmitting means to said start magnet to thereby prevent a digit entry corresponding to the digit represented by the hole sensed.
7. In a record controlled subtracting means controlled by record cards, wherein holes at four index point positions represent digit entries 2, 1, 3, 4, which entries singly or in combination represent all digits 1-9, means for sensing said index point positions to ascertain the presence of digit representing holes, an accumulator of the type in which a digit entry is initiated by energizing a start magnet, terminated by energizing a stop magnet, and energization of the start magnet and stop magnets concurrently prevents the initiation of a digit entry, impulse transmitting means for transmitting successive impulses coincident with sensing of the digit representing index points 2, 4 and at a subsequent time for a 3 digit entry to said start magnet to initiate corresponding digit entries in said accumulator to normally enter 9, further impulse transmitting means to transmit impulses to said stop magnet to terminate the 2, 4 and 3 digit entries, storing means, means under control of said sensing means for conditioning said storing means when a 3 digit representing hole is sensed, means under control of said sensing means for transmitting impulses to said stop magnet coincident with the impulses transmitted to said start magnet by the first named impulse transmitting means when the 2 and 4 digit representing holes are sensed to prevent a 2 or 4 digit entry, respectively, and to said stop magnet when a 1 digit hole is sensed at a time which shortens the 2 digit entry initiated by the first named impulse transmitting means to a 1 digit entry, and means under control of said conditioned storing means to transmit an impulse to said stop magnet coincident with the transmission of the impulse to said start magnet which initiates the 3 digit entry to thereby prevent the 3 digit entry.
8. In a record controlled subtracting means controlled by record cards, wherein holes at four index point positions represent digit entries 2, 1, and A and B entries which entries singly or in combination represent all digits 1-9, means for sensing said index point positions to ascertain the presence of digit representing holes, an accumulator of the type in which a digit entry is initiated by energizing a start magnet, terminated by energizing a stop magnet, and energization of the start magnet and stop magnets concurrently

prevents the initiation of a digit entry, impulse transmitting means for transmitting successive impulses coincident with sensing of the 2 and B digit representing index points and at a subsequent time for said A digit entry to said start magnet to initiate corresponding digit entries in said accumulator to normally enter 9, further impulse transmitting means to transmit impulses to said stop magnet to terminate the 2, and A and B entries, storing means, means under control of said sensing means for conditioning said storing means when said A digit representing hole is sensed, means under control of said sensing means for transmitting impulses to said stop magnet coincident with the impulses transmitted to said start magnet by the first named impulse transmitting means when the 2 and B digit representing holes are sensed to prevent a 2 or said B digit entry, respectively, and to said stop magnet when a 1 digit hole is sensed at a time which shortens the 2 digit entry initiated by the first named impulse transmitting means to a 1 digit entry, and means under control of said conditioned storing means to transmit an impulse to said stop magnet coincident with the transmission of the impulse to said start magnet which initiates said A digit entry to thereby prevent said A digit entry.

9. In a record controlled subtracting machine controlled by record cards wherein holes at two index point positions represent 2, 1, means for sensing said index point positions to ascertain the presence of digit representing holes, an accumulator of the type in which a digit entry is initiated by energizing a start magnet, terminated by energizing a stop magnet, and concurrent energization of said start and stop magnets prevents a digit entry, impulse transmitting means to transmit an impulse to said start magnet to initiate a 2 digit entry, impulse transmitting means to transmit an impulse to said stop magnet to terminate the 2 digit entry, and means under control of said sensing means to transmit an impulse to said stop magnet when a 2 digit representing hole is sensed concurrent with the impulse transmitted by the first named transmitting means to prevent said 2 digit entry, and to said stop magnet when a 1 hole is sensed

at a time which shortens the 2 digit entry initiated by the first named impulse transmitting means to a 1 digit entry.

10. In a record controlled subtracting machine controlled by record cards wherein holes at two index point positions represent 2, 1, means for sensing said index point positions to ascertain the presence of digit representing holes, an accumulator element, driving means therefor, a start magnet which is energized by an impulse to clutch said accumulator element to said driving means, a stop magnet which is energized by an impulse to declutch said accumulator element from said driving means, and concurrent energization of said start and stop magnets prevents a digit entry, impulse transmitting means to transmit an impulse to said start magnet to initiate a 2 digit entry, means to declutch said accumulator element from said driving means to terminate the 2 digit entry, and means under control of said sensing means to transmit an impulse to said stop magnet when a 2 digit representing hole is sensed concurrent with the impulse transmitted by said impulse transmitting means to prevent said 2 digit entry, and to said stop magnet when a 1 hole is sensed at a time which shortens the 2 digit entry initiated by the impulse transmitting means to a 1 digit entry.

Certificate of Correction

Patent No. 2,439,445.

April 13, 1948.

HORACE S. BEATTIE

It is hereby certified that errors appear in the printed specification of the above numbered patent requiring correction as follows: Column 12, line 43, before the word "hole" strike out the numeral 3; column 13, line 22, before "start" insert *said*; line 23, for "two other entries" read *two other digit entries*; and that the said Letters Patent should be read with these corrections therein that the same may conform to the record of the case in the Patent Office.

Signed and sealed this 1st day of June, A. D. 1948.
